(57) **CLAIM**

The ornamental design for an apparatus for converting organic waste into gas and fertilizer, as shown and described in the preceding figures.

DESCRIPTION

FIG. 1 is a front perspective view of an apparatus for converting organic waste into gas and fertilizer.

FIG. 2 is a rear perspective view thereof;

FIG. 3 is a front view thereof;

FIG. 4 is a back view thereof;

FIG. 5 is a right side view thereof;

FIG. 6 is a left side view thereof;

FIG. 7 is a top view;

FIG. 8 is a bottom view;

FIG. 9 is a front perspective open view thereof;

FIG. 10 is a rear perspective open view thereof;

FIG. 11 is a front side open view thereof;

FIG. 12 is a back side open view thereof;

(Continued)

FIG. 13 is a right side open view thereof;
FIG. 14 is a left side open view thereof;
FIG. 15 is a top side open view thereof; and,
FIG. 16 is a bottom side open view thereof.
The broken line showings of FIGS. 9, 10 and 15 are for
illustrative purposes only and form no part of the claimed
design.

1 Claim, 16 Drawing Sheets
